UNITED STATES PATENT OFFICE.

JOHN M. DEXTER, OF ELMIRA, NEW YORK.

COAL-OIL LAMP.

SPECIFICATION forming part of Letters Patent No. 258,223, dated May 23, 1882.

Application filed December 22, 1881. (No model.)

To all whom it may concern:

Be it known that I, JOHN M. DEXTER, a citizen of the United States, and a resident of Elmira, Chemung county, New York, have invented certain Improvements in Coal-Oil Lamps, of which the following is a specification.

The objects of my invention are to secure the center socket-tube of a coal-oil lamp firmly in place, and at the same time prevent the escape of oil to the sides of the lamp, and this I effect by the construction hereinafter described, and shown in the accompanying drawings, in which—

15 Figure 1 is an elevation in section of sufficient of a coal-oil lamp to show my improvement; Figs. 2 and 3, sections showing modifications. Fig. 4 is a plan of the reservoir-top, Fig. 3. Fig. 5 is a plan of the socket-tube, Fig. 3.

The top of the lamp-reservoir A may be recessed, as in the lamp described in Letters Patent granted to me January 25, 1881, No. 236,937, and the center socket-tube, B, may be provided 25 with lips d to bear against the under side of the top b of the reservoir, the tube being drawn upward by turning a flanged or collar plate, D, as described in the Letters Patent granted to me January 25, 1881, No. 236,996.

30 To prevent any flow of oil from the burner to the sides of the reservoir over the collar-plate, I form in the latter, between its edge and the tube B, a recess, e, preferably annular, of such depth as to collect and retain any oil that 35 may flow into the plate.

In some cases, especially where the neck e of the collar-plate is high, it is best to form an inward downwardly-inclined flange, w, with a threaded socket to receive the tube B, so as 40 to permit the burner to be set well down toward the reservoir. In such case a part of the oil may drip down onto the top b of the reservoir, and as the latter is inclined the oil will flow inward toward the tube B and down 45 between the latter and the edge of the central opening in the top.

As there is sometimes a tendency of the oil to spread in a thin film over the top and toward the edge of the reservoir, especially when 50 covered by the plate D, that prevents evapora-

tion, I interpose between the plate and the top of the reservoir a packing, h, of bibulous paper or other material that effectually prevents any flow beyond it.

To avoid the use of two thick packing when the plate sets well up from the reservoir, I form on the latter an annular rib, i, upon which the packing may be compressed, and to secure a better hold upon the seat and a better joint I corrugate the top surface of the same, as 55 shown.

In the modifications Figs. 3, 4, and 5 the top of the reservoir has a notch, s, to receive a lip, d, formed by pressing out the side of the tube B, which lip is passed through the notch, 60 and the tube is then turned to the position shown in Fig. 3, being thus held vertically. A detachable V-shaped key, F, fits between shoulders t t of the tube and into the notch s, and prevents the tube from turning. The packing h is interposed between the sunken portion e of the collar-plate and the top of the reservoir. 70

I claim—

1. The combination, with a lamp-reservoir, 75 A, of a central tube, B, and means for connecting it detachably to the reservoir, and collar-plate D, screwing upon said tube, extending toward the sides of the reservoir and provided with a recess, e, substantially as set forth. 80

2. The combination of the reservoir having a centrally-depressed top, tube B, and a plate, D, having a recess, e, and downwardly-inclined screw-flange w, as set forth.

3. The combination of the reservoir, collar- 85 plate, and packing h, as set forth.

4. The reservoir provided with an annular raised serrated seat for the packing, substantially as described.

5. The combination of the notched reservoir, tube B, having a lip, d, and shoulders t t, and detachable key F, substantially as set forth. 90

In testimony whereof I have signed my name to this specification in the presence of two subscribing witnesses.

JOHN M. DEXTER.
